UNITED STATES PATENT OFFICE.

STANLEY J. JEMBRZYCKI, OF CHICAGO, ILLINOIS.

HAIR CLIPPER.

Application filed December 13, 1923. Serial No. 630,304.

To all whom it may concern:

Be it known that I, STANLEY J. JEMBRZYCKI, a citizen of the United States, and a resident of Chicago, in the county of Cook 5 and State of Illinois, have invented certain new and useful Improvements in Hair Clippers, of which the following is a specification.

This invention relates to improvements in hair clippers and more especially to an improved construction for a motor driven clipping or shearing implement.

The principal object of the invention is to provide a more efficient and dependable clipper for hair cutting purposes, embodying 15 an improved type of driving mechanism, calculated to transmit a reciprocatory movement to the movable cutting blade, without excessive vibration, chattering and noise.

A further object is to improve the general 20 design of the implement with a view to obtain better balance and distribution of weight, and greater ease of manipulation in the hand of the operator and finally, to attain greater simplicity in construction and 25 adjustment.

A preferred embodiment of the invention is disclosed in the accompanying drawings, in which,

Figure 1 is a perspective view of the complete clipper,

Figure 2 is a sectional view taken on the longitudinal axis of the clipper,

Figure 3 is an enlarged cross sectional view taken on line 3—3, of Figure 2.

Figure 4 is a top plan view with cover and tension plate removed, and portions broken away to show the complete drive.

Figure 5 is an enlarged detail view in section taken on line 5—5 of Figure 2.

Figure 6 is a perspective view of the cover plate, and

Figure 7 is a perspective view of the tension plate.

Figure 1 clearly shows the general design and arrangement of the parts of the 45 complete clipper, which comprises a body or handle 1, shaped to fit comfortably and naturally in the hand of the operator, fixed and movable cutting blades 2 and 3, set 50 oblique to the handle at the forward end thereof, a flexible shaft cable 4, leading into the rear end of the handle, and a slot 5, near the rear end for suspending the clipper upon the stand or other support when not 55 in use.

The handle or body 1 is preferably of solid metal of sufficient weight to give stability, with cavities or depressions formed therein to house the several driving elements, and normally concealed by a cover plate 6, 60 fitting over the cavities and lying flush with the top surface of the body.

The cutting blades 2 and 3, are similar in all respects to those used in the ordinary hand clipper, the fixed blade 2 being secured to the body and against an oblique face 1^a at the forward end thereof by means of screws or other fastening means. The cutting edges of the fixed blade extend beyond the body and have the usual toothed or 65 comb-like construction. The movable blade 3, bears upon the fixed blade and travels lengthwise thereof at a high speed of reciprocatory movement whereby the two sets of cutting teeth accomplish the cutting in 70 the usual manner.

The body 1, forming the handle of the clipper, is of a somewhat irregular shape, wider at the central portion and tapering away toward the ends, so as to fit comfortably in the hand of the operator. As clearly 75 shown in Figure 3, the body is generally rectangular in cross section with its top, bottom and side faces slightly convex. At the forward end of the handle a V-shaped 80 space is formed between the upper portion of fixed blade 2 and the adjacent edge of the body,—just above the under portion to which said fixed blade is attached. It is within this V-shaped space that the movable 85 blade is mounted, together with the posts connecting the blade with the driving mechanism.

Referring now to the moving parts which 90 impart the reciprocatory movement to the cutting blade 3, the same are located within a relatively shallow triangular shaped cavity 7, extending longitudinally and arranged 95 symmetrically of the body near its forward end. Within a well 8, sunk below the larger 100 end of the cavity 7 is mounted a worm wheel 9, journaled upon a stud 10. In the plane of this well and extending tangentially thereto is a passage 11 opening through the rear end of the body. At the forward end 105 of this passage is journaled a worm shaft 12, meshing with the worm wheel 9 and connected with an end fitting of the flexible shaft of the usual construction, enclosed 110 within the wall 4. The end fitting of the

shaft is yieldably held in driving connection, by means of a spring pressed ball lock 14, engaging an annular groove 13^a in the fitting.

5 Journalled on the top face of the worm wheel 9 is an eccentrically disposed crank pin or block 14, projecting upwardly into the cavity 7. This block is slotted diametrically to slidably engage one end of an oscillatory lever 15, in the form of a bar extending longitudinally of the cavity, and journalled near its opposite end, upon a post 16, anchored in the body at the forward end of the cavity and just inwardly from the forward edge of the body 1. The post 16, has an enlarged journal bearing 16^a engaged by a bearing sleeve 15^a of the lever 15. Beyond the journal bearing extends the short arm of the lever 15, having the form of a yoke 17 projecting beyond the edge of the body, and engaging a pin 18, preferably formed integral with the movable blade 3, the axis of said pin being parallel with that of the post 16, and oblique to the plane of the blade. To accommodate the yoke, the metal surrounding the pin is cut away in the form of a semi-circular cavity 18^a concentric with the axis of the pin.

20 It is manifest that the flexible shaft drives the worm wheel at a reduced speed through the intermediate worm drive, and the rotary movement of the worm wheel is translated into an oscillatory movement of the lever bar 15 through the medium of the sliding bar and crank connection. The yoke 17 being considerably shorter than the crank end of the lever, the oscillations are transmitted to the movable blade as a rapid reciprocatory motion of short stroke.

25 The cover plate 6 has already been described generally as fitting over the cavity 7, and as a preferred feature of construction, the plate is counter-sunk into the body, so that the surfaces of the plate and body are flush. The cover plate 6, Figure 6, is provided with an aperture 6^a which engages the post 16, and further, has a forward end portion 19 which projects beyond the edge of the body, its forward edge resting substantially in contact with the oblique face of the near blade 3. Moreover, there are formed on either side of the projecting portion 19, integral ears 20-20, bent at right angles to the plate, said ears converging to a point to fit snugly in the V-shaped space at the intersection of the cutting blade and the forward edge of the body 1. These ears 20-20 embrace the pin and yoke connection and together with the projecting portion 19, form a complete closure about the moving posts sufficiently tight to prevent the hair from working into the space and interfering with the operation of the implement.

30 Mounted on top of the body and adjacent the cutting end is a tension plate 21, shaped to extend the full width of the body adjacent the cutting blades and converging rearwardly therefrom and terminating near the central portion of the cover plate, in a rounded end portion 21^a. The plate is spaced above the body by the provision of a marginal flange 22, which bears on the surface of the body. The rounded end of the tension plate is concentric with and surrounds a circular boss 23, on the surface of the cover plate 6, which serves to position and limit the movement of the tension plate. The tension plate extends beyond the body with its forward edge in close proximity to the movable blade throughout its entire length, there being contact established between the blade and the plate by the provision of two bearing lugs 24-24, spaced inwardly from the ends and the forward edge of the plate. At either side of the tension plate and adjacent the forward end are transverse guard flanges 25-25, the same being continuations of the marginal flange 22, engaging the body 1. These guard flanges have oblique forward edges parallel with the plane of the blades which give them the same pointed or convergent shape as the ears 20, of the cover plate. As shown in Figure 1, these guard flanges overlap and embrace the forward side edges of the body and close the ends of the V-shaped channel between the blades and the body, thus affording greater protection against the accumulation of hair and dirt. The tension plate has a central aperture 26, through which the post 16 extends the latter projecting a short distance above and terminating in a threaded end, on which is mounted a knurled thumb nut 27 with a spring washer 28, between the nut and the tension plate 21. By tightening or loosening the nut 28, the pressure exerted by the lugs 24 at the edge of the plate 21 against the cutting blade 3 is adjusted to vary the bearing contact between the blades and hence their cutting action.

35 Having described the device embodying the invention, I claim as new and novel:

40 In a hair clipper, the combination of a body, fixed and movable blades mounted at one end of said body and arranged at an angle oblique to the longitudinal axis of said body and forming a V-shaped space between the movable blade and the adjacent end surface of said body, a post anchored in said body adjacent said blades, driving mechanism mounted in a cavity formed in said body and comprising an oscillatory lever journalled on said post and having pivotal connection with said movable blade, through the medium of a pin and yoke connection, and a worm and worm wheel in driving connection with said lever, a cover

plate for said recess having a portion extending to said movable blade, and provided with laterally spaced ears extending into the V-shaped space on either side of the point of pivotal connection of said lever with said blade, and a tension plate mounted on said post and having a marginal flange bearing upon said body and bearing

lugs engaging said movable blade, and a nut on said post and adjustable to vary the pressure exerted by said tension plate on said blade.

In witness whereof, I hereunto subscribe my name this 10th day of December, A. D., 1923.

STANLEY J. JEMBRZYCKI.
